(57) **CLAIM**

The ornamental design for an ice mold, as shown and described.

DESCRIPTION

FIG. 1 is a front perspective view of an ice mold showing my new design;

FIG. 2 is a rear elevation view of the ice mold of FIG. 1;
FIG. 3 is a left side elevation view of the ice mold of FIG. 1;

FIG. 4 is a right side elevation view of the ice mold of FIG. 1;

FIG. 5 is a top view of the ice mold of FIG. 1;

FIG. 6 is a bottom view of the ice mold of FIG. 1;

FIG. 7 is a top perspective view of the ice mold of FIG. 1; and,

FIG. 8 is a bottom perspective view of the ice mold of FIG. 1.

The broken lines shown in the drawings depict portions of the ice mold that form no part of the claimed design.
